[DESIGN.]

O. F. FOGELSTRAND.

Chain Bolt.

No. 5,500.

Patented Jan 30, 1872.

5,500

UNITED STATES PATENT OFFICE.

OTTO F. FOGELSTRAND, OF KENSINGTON, CONNECTICUT, ASSIGNOR TO HART
MANUFACTURING COMPANY, OF SAME PLACE.

DESIGN FOR A CHAIN-BOLT.

Specification forming part of Design No. 5,500, dated January 30, 1872.

To all whom it may concern:

Be it known that I, OTTO F. FOGELSTRAND, of Kensington, in the county of Hartford and State of Connecticut, have invented and produced a new and original Design for a Chain-Bolt, of which the following is a specification:

The nature of my design is fully represented in the accompanying engraving, to which reference is made.

A represents the bolt-case, and B the catch. A flange, b, extends from the sides and one end of these parts, as shown. The fronts of said parts A B b are surrounded by the band a, the spaces inclosed thereby having a checked or

roughened ground-work, upon which ground are the several raised ornamental figures, as shown. In the sides of the bolt-case A and catch B are pointed recesses c, the remaining surface of said sides being plain. The face of the bolt C at the chain end is ornamented by raised ledges crossing each other in diamond form.

I claim as my invention—

The design for a chain-bolt, as shown.

OTTO F. FOGELSTRAND.
